UNITED STATES PATENT OFFICE.

JAMES J. KEYS, OF BROOKLYN, NEW YORK.

ARCH-SUPPORT.

1,219,381.

Specification of Letters Patent. Patented Mar. 13, 1917.

Application filed May 16, 1916. Serial No. 97,901.

To all whom it may concern:

Be it known that I, JAMES J. KEYS, a citizen of the United States, residing at Brooklyn, in the county of Kings and State 5 of New York, have invented new and useful Improvements in Arch-Supports, of which the following is a specification.

This invention relates to arch supports adapted to be applied to shoes and it consists in the novel features hereinafter described and claimed.

The arch of the human foot is, or should be, supported by the shank of the shoe, and the shank as usually formed is sufficient 15 where the arch is normal. But when the wearer develops symptoms of a broken arch, the average shoe shank needs the reinforcement of a metallic stiffener or support in order to successfully resist the extra strain 20 thrown upon it. This strain comes between the heel of the foot which is supported by the heel of the shoe, and the ball of the foot which is supported by the shoe sole resting on the ground; and, while it is usually distributed throughout the length of the shank, 25 it does not always fall with equal effect across the width of the shank. That is to say, if we assume that a line is drawn along the arch of the foot substantially midway 30 between its outer and inner sides, that half of the arch on the outer side of such line is substantially flat transversely, whereas the other half on the inner side of such line is curved upward or arched transversely, while 35 both halves are curved upward or arched longitudinally as is made clear above. It follows that when the arch begins to break down under weakness of parts or increase of the load thrown upon it, an efficient me- 40 chanical support which braces the shank and causes the latter in turn to support the arch, must conform with the configuration of the foot both longitudinally and transversely and in great detail, whereas such 45 conformation is not necessary, and indeed the support itself may be omitted if the foot be normal.

In devices of this kind hitherto made, as far as I am aware, either the support was 50 inserted within the shank of the shoe, or if secured to the lower face thereof, it conformed with the longitudinal curvature quite accurately whereas it conformed with the transverse configuration with less accuracy. An object of the present invention is to give such shape to the metallic support

that it will sustain the shoe shank throughout both its width and length, and cause such shank to support the arch in a natural manner and therefore prevent its falling or 55 restore it if it has fallen.

An object of the invention is to provide a support of the character indicated which when applied will efficiently and effectually support the arch of the human foot in a 60 manner to prevent the falling or flattening of the arch and troubles incident thereto.

With this object in view the support comprises a plate adapted to be applied to the shank of the shoe immediately in advance of 65 the forward wall of the heel. The said plate is provided with a medial longitudinally located rib and the portion of the plate at one side of the rib is curved longitudinally to correspond with the longitudinal 70 curvature of the arch of the foot. The portion of the plate at the opposite side of the said medial rib is curved longitudinally and transversely. The longitudinal curve of the last mentioned portion corresponds approximately with the longitudinal curvature of 75 the foot while the transverse curvature of the said portion corresponds approximately with the transverse curvature of the arch of the foot. Consequently it will be seen that 80 when the support is applied the longitudinal and transverse arches of the foot are supported and falling or flattening of the arch 85 of the foot is prevented.

In the accompanying drawing:— 90

Figure 1 is a fragmentary view of a shoe showing the arch support applied.

Fig. 2 is a bottom plan view of a shoe adapted to be worn upon the left foot showing 95 the support applied.

Fig. 3 is a similar view of a shoe adapted to be worn upon the right foot.

Fig. 4 is a transverse sectional view of the shoe and the support cut on the line 4—4 of Fig. 1. 100

Fig. 5 is a perspective view of the arch support.

The arch support comprises a metallic plate 1 adapted to be secured by screws 2 or other suitable devices to the shank of a 105 shoe as illustrated in the drawing. When the plate 1 is in position upon the shank of the shoe the rear edge of the plate is in close contact with the forward wall of the heel.

The plate 1 is provided with a medial longitudinally disposed rib 3 the center of 110

which is rather deep or pronounced, while its ends fade out short of the ends of the plate. This rib is preferably formed in the plate by pressing or stamping, and it separates and defines two leaves. That numbered 4 which is located at the outer side of the rib 3 is curved upward or arched longitudinally and approximately corresponds with the longitudinal curvature of the arch of the human foot, whereas it is practically flat transversely. The leaf 5 at the opposite or inner side of the rib 3 is curved upward or arched both longitudinally and transversely. The longitudinal curvature thereof corresponds approximately with the longitudinal curvature of the arch of the foot, while the transverse curvature of this leaf corresponds approximately with the transverse curvature along the inner side of the arch of the foot.

Thus it will be seen that when the plate 1 is applied to the shank of a shoe the outer leaf 4 extends approximately parallel with the longitudinal arch of the foot while the inner leaf 5 extends under the transverse arch of the foot and supports this edge of the shank of the shoe up against the transverse arch of the foot as best indicated in Fig. 4 of the drawing.

The inner edge of the plate is slightly longer than the outer edge, that is to say, the

edge of the plate 1 which is located under the transverse arch of the foot when the shoe is applied is slightly longer than that edge of the plate which is beneath the longitudinal arch of the foot. 35

From the above description taken in conjunction with the accompanying drawing it will be seen that an arch support of simple and durable structure is provided and that 40 the same will efficiently and effectually support the longitudinal and transverse arches of the foot when the support is applied to a shank of the shoe as described.

Having described the invention what is 45 claimed is:—

The herein described arch support adapted for application to the lower face of a shoe shank, the same comprising a metal plate arched throughout its length to conform with the longitudinal curvature of said shank, provided between its edges with a depressed longitudinal rib which is pronounced at its midlength and runs out at its extremities near the ends of the plate, 50 the rib defining two leaves whereof that at the inner side of the support is transversely arched throughout its width and that at the outer side is transversely flat, and means for holding the plate in place. 55

In testimony whereof I affix my signature.
JAMES J. KEYS. 60
